UNITED STATES PATENT OFFICE.

FRANCES H. LANGSON, OF ST. FRANCIS, WISCONSIN.

SHUTTER-FASTENER.

SPECIFICATION forming part of Letters Patent No. 425,330, dated April 8, 1890.

Application filed January 30, 1890. Serial No. 338,565. (No model.)

To all whom it may concern:

Be it known that I, FRANCES H. LANGSON, a citizen of the United States of America, residing at St. Francis, in the county of Milwaukee and State of Wisconsin, have invented 5 certain new and useful Improvements in Cabinet-Hooks or Shutter-Fastenings; and I do hereby declare the following to be a full, clear, and exact description of the invention, such 10 as will enable others skilled in the art to which it appertains to make and use the same, reference being had to the accompanying drawings, and to letters of reference marked thereon, which form a part of this specifica- 15 tion.

This invention relates to certain new and useful improvements in cabinet-hooks.

The object of the invention is to provide a hook which has a knob formed opposite the 20 hook portion, with a perforation through which the securing-pin passes, so that the hook can be operated by the knob formed integral therewith, as and for the purposes hereinafter mentioned.

25 In the accompanying drawings, Figure 1 is a perspective view of a cabinet-hook constructed in accordance with my invention. Fig. 2 is a view showing the same applied to a pair of shutters, and Fig. 3 is a plan view 30 partly in section.

My improved hook is cast or made with all parts integral, and a suitable knob is formed through which is a perforation *a*, and the se-

curing-screw is passed through this knob and serves to hold the hook in place. Beneath 35 the knob portion of the hook *A* is formed an annular projection *b*, which keeps the body *c* of the hook, as well as the hook *d*, out of contact with the article to which it is attached. The knob is formed of sufficient height to be 40 easily grasped, and when the device is applied to a shutter, as shown in Fig. 2, the usual knob beneath the ordinary hook is dispensed with. The ordinary fastening can be used for engagement with the hook *d*. 45

This device may be used for fastening inside window-blinds, for which it is especially designed, or for other purposes for which cabinet-hooks are usually employed.

Having thus described my invention, what 50 I claim as new, and desire to secure by Letters Patent, is—

As an improved article of manufacture, a cabinet-hook made of a single piece and provided with the usual hook and body portion, 55 a knob formed integral therewith, said knob having a perforation through which passes the securing means, which serves as a pivot, substantially as shown, and for the purpose set forth. 60

In testimony whereof I affix my signature in presence of two witnesses.

FRANCES H. LANGSON.
